(57) **CLAIM**

The ornamental design for a paper towel holder, as shown and described.

DESCRIPTION

FIG. 1 is a perspective view of the paper towel holder showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof;

FIG. 8 is a bottom plan view of thereof; and,

FIG. 9 is a perspective view of thereof when it is being used. Broken lines are used to illustrate portions of the paper towel holder. Other broken lines illustrate environmental subject matter that form no part of the claimed design.
